US0D1101519S

(12) **United States Design Patent** (10) **Patent No.:** **US D1,101,519 S**
(45) **Date of Patent:** **** Nov. 11, 2025**

(54) **ICE CREAM SCOOP**

(71) Applicant: **Dongguan Keewey Electrical Technology Co., Ltd.**, Dongguan (CN)

(72) Inventors: **Yahan Huang**, Dongguan (CN); **Xiaona Chen**, Dongguan (CN)

(73) Assignee: **Dongguan Keewey Electrical Technology Co., Ltd.**, Dongguan (CN)

(**) Term: **15 Years**

(21) Appl. No.: **29/960,635**

(22) Filed: **Aug. 30, 2024**

(51) LOC (15) Cl. **07-04**

(52) U.S. Cl.

USPC **D7/681**

(58) **Field of Classification Search**

(57) **CLAIM**

The ornamental design for an ice cream scoop, as shown and described.

DESCRIPTION

FIG. 1 is a front perspective view of an ice cream scoop, showing our new design;

FIG. 2 is a rear perspective view thereof;

FIG. 3 is an enlarged front view thereof;

FIG. 4 is an enlarged rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
